UNITED STATES PATENT OFFICE.

ERNST HERKT, OF KIEL-HASSEE, GERMANY, ASSIGNOR TO FRIED. KRUPP GERMANIA-
WERFT AKTIENGESELLSCHAFT, OF KIEL-GAARDEN, GERMANY.

INTERNAL-COMBUSTION ENGINE.

Application filed January 21, 1925. Serial No. 3,846.

This invention relates to internal combustion engines in which the cross-head or piston is provided with a lateral arm for driving a pump. It has for its object to 5 provide an engine of the said character in which such a lateral arm has not only connected to it the piston rod of a scavenging pump but also the telescopic pipes for supply and discharge of the cooling water for 10 the working piston, whereby it is made possible to attain an especially advantageous construction of the engine.

An embodiment of the subject-matter of the invention is illustrated in the accompanying drawing in which:

Fig. 1 is a cross-section through a multi-cylinder internal combustion engine of the two-stroke type and

Fig. 2 a partial side elevation of the engine.

A is a cylinder of a multi-cylinder two-stroke internal combustion engine which is mounted on standards B¹, B². The piston C working in the cylinder A, transmits its 25 movement by the piston rod D to the cross-head E and from the latter by the connecting rod F to the crank G of the engine shaft. Connected to each of the working cylinders is a cylinder H of a scavenging pump. The 30 pump cylinder H has its bearing faces h¹ fastened to corresponding flanges a¹ of the working cylinder and is supported from below by a distance piece J which is fastened to the standards B¹ and provided with 35 an opening i¹. Mounted for reciprocation in the pump cylinder H is the piston K the piston rod L of which extends downwardly through the stuffing-box h² into the interior of the distance piece J. The scavenging 40 pump is double-acting. During the downward stroke of the piston K the air is drawn in from the atmosphere through valves M¹ and during the upward stroke through valves M² and, in the first case, it passes 45 through valves N¹ and, in the second case, through valves N² into the compressed air chamber h³ from where it passes into the scavenging slots a² of the working cylinder which are in direct communication with the 50 chamber h³. The side faces h⁴ of the air chamber h³ bear against the corresponding faces of the air chamber of the neighboring scavenging pumps. At their free front side the air chambers are closed by covers O.

The piston K of the scavenging pump is 55 driven by an arm P fastened to the cross-head of the engine, the piston rod L being in screw-threaded connection with the said arm. The arm P has, besides, connected to it the telescopic pipes R which serve to 60 supply and lead off the cooling water for the working cylinder C. These pipes extend at both sides of the pump piston rod L through the arm P with which they are in screw-threaded engagement. From the arm 65 P they extend on the one hand to the working piston C and on the other hand to a housing Q which is suspended from the distance piece J and provided with inlet and outlet pipes q for the cooling water.

By arranging the cylinder of the scavenging pump directly beside the working cylinder, it is attained that the passage of the scavenging air from the pump into the cylinder takes place on a short way so that 70 special air pipes which always entail losses of pressure, are dispensed with. Besides, by arranging the housings of the telescopic pipes likewise at the side of the engine, these delicate parts of the engine are rendered 75 easily accessible. The described arrangement of the pump cylinders and housings of the telescopic pipes on a common distance piece J finally allows of these parts being 80 carefully worked upon, accurately centered 85 and simply assembled. The distance piece may be bolted to or cast integrally with the crank casing or the standards.

Claims.

1. In a two-stroke internal combustion engine having a cylinder and a piston therein, a scavenging pump, a reservoir for receiving the air compressed by said pump, said reservoir being fixed directly beside the engine cylinder and communicating directly with the latter by a passage controlled by the engine piston, and an arm on a rectilinearly reciprocating engine element operatively connected to the piston of said scavenging pump.

2. In a two-stroke internal combustion engine having a cylinder and a piston therein, a scavenging pump, a jacket surrounding the cylinder of said pump and forming a reservoir for the air compressed by the latter, said jacket being disposed directly beside the engine cylinder and communicating directly therewith by a passage con-

trolled by the engine piston, and an arm on a rectilinearly reciprocating engine element operatively connected to the piston of said scavenging pump.

5. 3. In a two-stroke internal combustion engine, a water cooling system including telescopic pipes, a scavenging pump having its cylinder disposed directly beside the engine cylinder and communicating therewith, a 10 distance piece interposed between and fixed to said pump cylinder and the stationary element of said telescopic pipes for maintaining the two in operative alignment, and an arm on a rectilinearly reciprocating engine element operatively connected to the piston of said scavenging pump and to the movable element of said telescopic pipes.

4. In combination with a two-stroke internal combustion engine comprising a cylinder and piston therein whose piston rod is connected to a crosshead provided with a crosshead slipper on one side only, a scavenging pump arranged at one side of the cylinder comprising a cylinder, piston, and 25 piston rod, and an arm rigidly projecting from the crosshead on the side opposite the crosshead slipper, and connected to the piston rod of the scavenging pump.

5. In combination with a two-stroke internal combustion engine comprising a work cylinder and piston therein whose piston rod is connected to a crosshead provided with a crosshead slipper on one side only, a scavenging pump, comprising a cylinder, piston, 35 and piston rod, arranged beside the work cylinder with its cylinder at the same height as the work cylinder, a chamber arranged to take the compressed air from the pump, the chamber being built onto the work cylinder and communicating therewith through a 40 continuously open passage, and an arm

rigidly projecting from the crosshead and connected to the connecting rod of the scavenging pump.

6. In combination with a two-stroke internal combustion engine comprising a work cylinder and piston therein whose piston rod is connected to a crosshead provided with a crosshead slipper on one side only, a scavenging pump, comprising a cylinder, piston, 50 and piston rod arranged beside the work cylinder with its cylinder at the same height as the work cylinder, a casing surrounding the scavenging pump cylinder and forming a reservoir for the compressed air from the pump, said casing being fastened to the work cylinder and communicating therewith through a continuously open passage, and an arm rigidly projecting from the crosshead and connected to the piston rod of the 55 scavenging pump.

7. In combination with a two-stroke internal combustion engine comprising a cylinder and a piston therein whose piston rod is connected to a crosshead provided with a crosshead slipper on one side only, a scavenging pump comprising a cylinder, piston, and a piston rod, arranged beside the work cylinder, a water cooling system including 60 telescopic pipes, a distance piece inserted between and rigidly connected to the scavenging pump cylinder and the stationary element of the telescopic pipes to hold them in operative alignment, and an arm rigidly projecting from the crosshead and 65 connected to the piston rod of the scavenging pump and the movable element of the telescopic pipes.

The foregoing specification signed at Hamburg, Germany, this 11th day of December, 1924.

ERNST HERKT.
